UNITED STATES PATENT OFFICE.

JOHN K. HOLBROOK, OF NEWARK, NEW JERSEY, ASSIGNOR TO D. S. PLUMB, OF EAST ORANGE, NEW JERSEY.

APPARATUS FOR REPRODUCING VIEWS IN COLOR.

1,151,786.

Specification of Letters Patent. Patented Aug. 31, 1915.

Application filed March 22, 1913. Serial No. 756,188.

To all whom it may concern:

Be it known that I, JOHN K. HOLBROOK, a citizen of the United States, residing at and whose post-office address is No. 873 5 South Sixteenth street, Newark, county of Essex, State of New Jersey, have invented certain new and useful Improvements in Apparatus for Reproducing Views in Color; and I do hereby declare the following to be 10 a full, clear, and exact description of the invention, such as will enable others skilled in the art to which it appertains to make and use the same.

The invention relates to the reproduction by photography and projection of scenes and objects appearing in approximately their natural colors, and it particularly comprehends an organization of reasonably inexpensive apparatus for producing a lantern 15 slide, or the like, bearing photographic impressions of a plurality of separate images of the scene or object, each impression being made by light rays of a particular selected color, so that the said images will have different color values, and all of said images 20 being capable of recombination, by suitable projecting apparatus, into a colored image of the scene or object, without the exercise of an excessive degree of skill on the part of the operator. To this end I provide apparatus for decomposing the image of the scene or object into a plurality of separate substantially like images formed through closely associated edge portions of reversed 25 sectors of the same lens, producing said separate images in different colors by interposing color screens in the paths of their rays, and making a single lantern slide containing photographic impressions of said plurality of separate and variously colored 30 images.

The apparatus comprises a camera provided with a lens which consists of recomposed reversed sectors cut from a single lens 45 so that the edges of the original lens meet in the center of the recomposed lens and the diaphragm apertures are closely associated around the center. This close association of the diaphragm apertures reduces stereoscopic effect in the separate images produced to a negligible amount. The reversal of the segments brings the original center of the lens to a plurality of points upon the periphery of the recomposed lens and produces a

plurality of axes which define the separation of the plurality of images formed.

In apparatus intended for the use of the public in general it is not practicable to employ an expensive camera lens which is fully corrected and it is, therefore, of great 50 advantage to employ a lens of the type which most nearly approaches the desired ideal and which, by the development of its mode of manufacture, has become a commercial article producible at a cost which makes 55 it available as an element of the apparatus under discussion. Such a lens, available at a low cost is found to contain all the necessary corrections except that for distortion of the red rays which are not usually made use 60 of with ordinary photographic work. By making use of a projecting apparatus disclosed in this application as originally filed and now, by the requirement of the Patent 65 Office, presented in a division application, 70 Serial No. 872,672 filed November 18, 1914, I am enabled to correct extraneously for the distortion of the red image alone without 75 interposing disturbing elements in the already corrected portions of the system. 80

I have illustrated in the accompanying drawings apparatus embodying my invention in a manner well suited to a clear understanding of the working thereof, Figure 1 being a central horizontal section of the 85 camera which I employ; Fig. 2, a section on line 2—2 of Fig. 1; Fig. 3, a section on line 3—3 of Fig. 1; Figs. 4, 5, 6 and 7, four views showing steps in the construction of one element of the camera lens; and Fig. 8, 90 a view in perspective of the assembled camera lens showing the lens tube broken away.

Referring to the drawings, the camera lens is made up of elements *a* which are, in ordinary lenses, of the circular shape shown 95 in Fig. 4. I prefer to first grind the edges of these elements *a* to the hexagonal form shown in Fig. 5 and then cut them into segments *b*, *c*, *d* as indicated in Fig. 6. The arrows shown in Figs. 4, 5, 6 and 7 indicate the position of the lens material in these views. It will be noted that the segments *b*, *c*, and *d* (Fig. 6) are of a regular diamond shape, their inner cut edges being identical as regards length and angle with their outer ground edges. I now reverse 100 these segments *b*, *c* and *d* bringing their outer ground edges together and cement 105

them, recomposing the lens in hexagonal form with the edge portions of the original element *a* at the center of the recomposed lens element and the central portions of the original element *a* at three equi-distant points on the edge of the recomposed lens element. In grinding the hexagonal shape upon the edge of the original lens element *a* care should be taken to keep the straight ground edges parallel to the axis of the lens so that when the segments are reversed and cemented the three separated axes of the recomposed lens element will be parallel. The lens is now assembled, preferably in a hexagonal tube *f* with the usual spacing pieces and three leafed partitions *e* interposed between the spaced elements to avoid the crossing of light. This assembly of the hexagonal lens elements in a hexagonal lens tube maintains the several sectors of the several lens elements in alinement. The lens tube *f* is then preferably mounted in a hexagonal sleeve *g*, the hexagonal form of which prevents the lens tube from rotating but permits it to slide axially for focusing. The lens tube and its sleeve may be provided with the usual rack and pinion device for producing axial movement of the lens tube in focusing. The camera box *A* shown in Figs. 1, 2 and 3 is of the usual type, and it is provided with a plate holder *B* which may be inserted and withdrawn, being held in the camera plates by a spring clip *C*. From a point just back of the lens tube *f* partitions *D* are so arranged that their forward ends coincide with the lines of juncture of the sectors of the lens to prevent stray rays of light passing through one sector from crossing to the field of another sector. The rearward ends of the partitions *D* engage partitions *E* which exercise the same functions and extend backwardly to within a short distance of the ground glass shown at *E'* in Fig. 1 and which occupies a position identical with that of the plate when the plate holder is inserted. The partitions *E* divide the surface of the plate into three parts upon each of which one of the colored images from the lens falls.

The different color values may be obtained by coloring the lens segments *b*, *c* and *d*, or an additional screen may be provided, such as shown at *i*.

The diaphragm *h* which is located within the lens tube has three apertures one opposite each sector of the lens, and these apertures are placed as closely together and to the center of the lens as is practicable. The areas of these apertures in the diaphragm are proportioned one to another in such a way that the amount of light necessary for each of the colored images to be properly impressed upon the plate will be admitted by a single exposure, that is by the removal

of the cap from the lens simultaneously admitting light to all three diaphragm apertures and the subsequent return of the cap simultaneously cutting off the light from all three diaphragm apertures.

When an exposure has been made upon a plate in this way, the plate upon development will give a negative containing three separate negative pictures having relatively correct color values if the exposure has been approximately correct. From this negative a positive lantern slide is to be made in the usual way. If an inexpensive lens is employed which is reasonably correct for ordinary photographic purposes, it is usually found that the negative and positive pictures produced by the red or orange light, as the case may be, show distortion and are therefore not of exactly the same size as the pictures produced by the green and violet or the blue and yellow lights, and this is so because the lens is not usually corrected for the red and orange as the colors do not play an active part in the usual photographic processes. This distortion may, however, be corrected by projecting apparatus embodying the invention disclosed in my pending application above referred to.

It will be obvious that but two pictures may be taken upon a slide or more than three when the colors are chosen to produce the color effects desired.

What I claim is:

1. In a camera for use in the reproduction of scenes and objects in color by photography and projection, a lens tube and a lens associated therewith and made up of recomposed and closely positioned reversed sectors of a given lens, whereby the normal image of such given lens is decomposed into a plurality of separate but closely associated images.

2. In a camera for use in the reproduction of scenes and objects in color by photography and projection, a lens made up of recomposed reversed sectors of a given lens, and color screens interposed in the paths of the image-forming light rays passing through the several sectors, whereby the normal image of such given lens is decomposed into a plurality of separate but closely associated images of different color value.

3. In a camera for use in the reproduction of scenes and objects in color by photography and projection, a lens made up of recomposed reversed sectors of a given lens, color screens interposed in the paths of the image-forming light rays passing through the several sectors, and a diaphragm having a plurality of apertures corresponding to the plurality of sectors, the areas of the several apertures being proportioned to one another in accordance with the amount of light required for the several colored images, whereby the normal image of such given lens is

decomposed into a plurality of separate but closely associated images of different color value and appropriate relative intensity.

4. A camera for use in the reproduction of scenes and objects in color by photography and projection, having means for dividing a beam of light from the scene or object into a plurality of slightly separated beams and for screening from each of the 10 separate beams light rays of different colors, to form a plurality of separate but closely associated images of different color value, said dividing means comprising a lens made up of recomposed reversed sectors of a given 15 lens, substantially as described.

5. In a camera for use in the reproduction of scenes and objects in color by photography and projection, a lens associated therewith made up of closely positioned sectors, the adjacent side edges of which are 2 radially contiguous, said sectors being capable of producing separate images, for the purpose described.

In testimony whereof I affix my signature, in presence of two witnesses.

JOHN K. HOLBROOK.
